UNITED STATES PATENT OFFICE.

ROGER W. CONANT, OF BOSTON, MASSACHUSETTS.

GAME.

SPECIFICATION forming part of Letters Patent No. 673,535, dated May 7, 1901.

Application filed June 28, 1900. Serial No. 21,948. (No model.)

To all whom it may concern:

Be it known that I, ROGER W. CONANT, a citizen of the United States, residing in Boston, in the county of Suffolk and State of Massachusetts, have invented an Improvement in Games, of which the following description, in connection with the accompanying drawings, is a specification, like characters on the drawings representing like parts.

10 This invention relates to a game especially designed and adapted to be played indoors, and particularly in the parlor or other room of a house.

In accordance with this invention I employ 15 an automatically-returning roller provided with an index or pointer and with a series of divisions or numbers with which the index co-operates and which correspond to spaces formed or outlined on the floor or other flat 20 surface. The game is played by standing a predetermined distance from the spaces, and after turning the index on the roller and allowing the same to come to rest the roller is rolled along the floor toward the spaces, and 25 the object is to cause the roller to stop on its forward movement in the space corresponding to the indication on the roller at which the index has stopped. The roller is constructed so that its forward movement stores 30 up energy sufficient to cause it to return to the player. The game is won by the player who succeeds in rolling the roller into the designated spaces the greatest number of times in a given number of trials. These and 35 other features of this invention will be pointed out in the claims at the end of this specification.

Figure 1 is a plan view representing a game embodying this invention; Fig. 2, an index 40 view of the roller; Fig. 3, a front or side elevation of the roller; and Fig. 4, a longitudinal section of the roller on the line 4-4, Fig. 2.

The automatic returning roller with which to practice the game consists of a cylinder *a*, 45 provided with heads *b c*, through openings in which extend the ends of one or more elastic bands *d*, secured to the said heads by pins *e*, and upon which is hung by staples *f* bar *g*, preferably of wood, to which is secured on its 50 under side a piece or bar *h*, of metal, constituting a weight. The staples *f* embrace both pieces or members of the elastic bands, and

the bar *g* at or near its center is provided with a projection *i*, which may be a small nail or brad, which extends upward between 55 the pieces or members of the elastic bands. The cylinder *a* is provided at its opposite ends with caps *j k*, one of which, as *k*, is provided on its end with spaces herein marked "1," "2," "3," (see Fig. 2;) but other indications 60 may be employed and the number may be increased or diminished. The cap *k* carries a revoluble index or pointer *m*, adapted to turn on a stud *n*.

Upon the floor of a room or on a flat surface, such as a table, is marked off or formed a series of spaces, which may be numbered "1," "2," "3," as in Fig. 1, to correspond with the marks or numbers on the end of the roller with which the pointer or index co-operates, or the number on the spaces may be omitted. The spaces "1" "2" "3" may be formed by pieces *o* of flexible material, preferably tape, arranged substantially parallel to one another and to a tape *p* on the floor, 75 and the said pieces of tape may be held flat by suitable weights.

The players stand off a predetermined distance, (represented by the line *q*,) and each player is entitled to a number of rolls—say, 80 for instance, three—and the player succeeding in rolling the roller the highest number of times so that it stops on its forward movement in the space corresponding to the number on the roller at which the pointer stops 85 after being set in motion by the player previous to each roll wins the game. In other words, a player standing back of the line *q* strikes the pointer or index *m* and allows it to come to rest, which, as shown in Fig. 2, is 90 at the division marked "3." He then rolls the roller along the floor toward the marked spaces and endeavors to roll the roller with just sufficient force so that it will stop on its forward movement in the space marked "3." 95 If the roller stops on its forward movement in any other space—as, for instance, in the space marked "2" or beyond the marked spaces, as indicated by dotted lines—a miss is counted. The roller on its forward movement winds up the elastic bands and stores up sufficient energy to automatically return to the starting position, whereupon the same player or a new one tries to score. It is also

a part of the game to roll the roller so that on its return movement it will recross the nearer boundary-line of the designated space, and if the roller is rolled by the player so that on its return movement it does not recross the nearer boundary-line a miss is counted even if the roller stops on its forward movement in the designated space.

The weight is freely suspended from the elastic bands near their fixed ends, so that the bands will sag a minimum amount, and thus enable a cylinder or roller of minimum diameter to be employed, and this method of suspending the weight also permits free movement of the portions of the bands on which the weight rests with relation to the weight itself, which avoids drawing the weight to one side of its normal or proper position, which would cause friction between the weight and the end of the cylinder and impede the motion of the roller.

I claim—

1. A game apparatus comprising a plu-

rality of flexible pieces adapted to be laid substantially parallel on a substantially flat 25 surface to form a series of spaces, and an automatic returning roller provided with a revolute index and with indications coöperating with said index and corresponding to the spaces formed by the flexible pieces, substantially as described.

2. An automatic return - roller provided with indications and with a pointer or index coöperating with said indications, and means within the roller operated by the forward 35 movement of the roller to store up energy to automatically return said roller to its starting position, substantially as described.

In testimony whereof I have signed my name to this specification in the presence of 40 two subscribing witnesses.

ROGER W. CONANT.
